GUSTAVE GLOCKER, OF WASHINGTON, DISTRICT OF COLUMBIA.

NON-REFILLABLE BOTTLE.

1,202,055.

Specification of Letters Patent.

Patented Oct. 24, 1916.

Application filed May 23, 1914. Serial No. 840,589.

To all whom it may concern:

Be it known that I, GUSTAVE GLOCKER, a citizen of the United States, residing at Washington, in the District of Columbia, have invented a new and useful Non-Refillable Bottle, of which the following is a specification.

The present invention relates to improvements in non-refillable bottles, one object of 10 the present invention, being the provision of means adapted to be attached to the neck of a bottle to prevent the same from being refilled, but which will permit the liquid to flow from the bottle when the same is 15 tilted beyond a horizontal plane and will reseat itself before the bottle is returned to a horizontal plane.

A further object of the present invention is the provision of a valve and protecting 20 member for the valve, both of which are loosely mounted within a cap, the valve being protected by the protecting member so that an outside implement cannot engage the valve to hold the same from the seat, 25 while the protecting member, when the bottle is in a vertical position will insure the centering of the valve to prevent the flow of liquid into the bottle.

A still further object of the present invention is the provision of a valve and protecting member for a non-refillable bottle, so arranged that the tendency for a 30 vacuum within the bottle will cause the valve to seat and thus prevent the inrush of liquid 35 into the bottle, while the protecting member will prevent the introduction of a tool to engage the valve to hold it from the seat.

A still further object of the present invention, is the provision of a non-refillable 40 bottle, which is simple, inexpensive and durable in construction, and which may be readily attached to the neck of a bottle with small expense.

In designing a non-refillable bottle, a 45 number of features must be considered, the first and primary one is the cost of manufacture and installation, secondly, the protection of the valve so that the same will not be held open to permit of the refilling of the 50 bottle either when submerged or when a vacuum is created within the bottle. To this end, the present non-refillable bottle is provided with an apertured gasket which constitutes a valve seat and a cap which is 55 clamped upon the mouth of the bottle by means of a soft metal spun sleeve, such cap

having contained therein, a frusto-conical valve, the face of which normally rests upon to seal the aperture in the gasket, in combination with a valve protector which is hollowed upon its under side to fit upon the frusto-conical valve to insure the centering and seating thereof upon the gasket when the bottle is in a vertical position, the parts being so arranged as to be independent of each other so that when the bottle is tilted beyond the horizontal, the protector will move forwardly to permit the valve to slide downwardly and, when the valve is of a relatively smaller diameter and where the 60 port through the seat is provided with peripheral projections, will uncover one or more of such projections sufficiently to permit of the introduction of air to assist in the flowing of the liquid, so that when the 65 bottle is further tilted, the valve is permitted to tilt toward the mouth of the cap and away from the gasket. By this means, when the parts are in any position and the fluid is drained and a hose is connected to 70 create a vacuum within the bottle, there is no way to hold the valve from its seat so that the instant the suction from the outer face of the valve is released, the vacuum effect within the bottle will cause the valve 75 to be drawn upon its seat and thus seal the aperture in the gasket so that liquid cannot enter the bottle. As the protecting member is provided to be loosely mounted within the cap, and is of such a diameter as to prevent the introduction of a tool through the 80 opening in the cap to hold the same so that the valve may be reached, it is thus impossible to hold both members so that a 85 liquid can be introduced through the aperture of the gasket.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings, Figure 1 is a vertical sectional view through the neck of a bottle with the present non-refillable attachment connected thereto and in normally closed position. Fig. 2 is a similar view showing the parts in the position they

assume when the bottle is in a horizontal position. Fig. 3 is a similar view showing the parts in the position they assume when the bottle is tilted for pouring the liquid therefrom. Fig. 4 is a bottom plan view of the cap showing the position of the protecting ribs therein. Figs. 5 and 6 are top and bottom perspective views respectively of the valve protector. Fig. 7 is a perspective view 10 of the valve. Fig. 8 is a plan view of the valve seat and gasket. Fig. 9 is a plan view of a modified form. Fig. 10 is a vertical central sectional view through a modified form of the present invention. Fig. 11 15 is a similar view to Fig. 2 showing the gasket or valve seat as shown in Fig. 9 properly assembled with the parts.

Referring to the drawings, 11 designates 20 the neck of the bottle which is provided with the gasket receiving end 12 for the reception of the disk gasket 13, which is provided, as shown in Figs. 1 and 8, with the circular aperture 14, or as shown in Fig. 9, the gasket 13' is provided with the star-shaped aperture 14'.

The cap member 15 whose rim 16 is held 30 upon the gasket 13 by means of the spun clamping band 18 is provided with the shouldered portion 17 so that the spun metal clamping band 18 may be properly placed thereupon to hold the parts in their proper assembled positions, as shown in Figs. 1, 2 and 3. The central aperture or outlet 19 is provided, there being a rim or flange 21 35 surrounding the same upon the inner side of the cap 15, the bottle when having been filled and the parts properly clamped in place, being provided with the cork 21 to stop the opening or aperture 19, thus reducing the cost of the usual stopper employed 40 in connection with these bottles. Upon the inner side of the cap 15 are a plurality of ribs 22, which are provided with the inclined ends 23 and with the abrupt inclined shouldered portions 24, these ribs constituting 45 guiding members for the valve protector 25 and also holding the periphery of such protector away from the cap so as to provide liquid passages around the protector when 50 the parts are in the position, as shown in Fig. 3. The cylindrical portion of the protector 25 is guided between the ribs so as to have an approximately straight line movement, the flaring rim 27 being disposed, 55 when the parts are in the positions as shown in Figs. 2 and 3, to seat against the inclined shoulders 24 of the ribs 22 and thus permit the movement of the protector toward the 60 outlet end of the cap. The edge 28, as shown, is cylindrical, while the inner face of the rim 29 is beveled or inclined, so as to receive the inclined face of the frusto-conical valve member 30. This valve member 30 as clearly shown in Fig. 1, is disposed to fit 65 upon the face of the gasket 13 or 13' and

thus fully cover the outlet opening 14 or 14', the protector 25 when in its lowermost position, due to gravity, engaging the same to center it, and thus hold it as clearly illustrated in Fig. 1, so that no liquid can enter 70 the opening 14 or 14' when it has passed beyond the gasket 13 or 13', or when it is poured in through the opening 19.

The flat face 31 of the frusto-conical valve member 30, is adapted to fit flush upon the 75 outer face of the gasket 13 or 13' and as its greatest diameter is greater than the diameter or the greatest width of the aperture 14 or 14', it is readily apparent that with the protector 25 resting upon the valve and constituting a weight holds the same centered and in the position, as shown in Fig. 1, and thus it will be impossible for liquid, even though forced, to enter the opening 14 or 14' and consequently the bottle. 85

Assuming that a vacuum is created by placing a hose about the cap 15, with the aperture 19 open, the valve 30 will be raised from its seat, the member 25 being elevated to assume the position, as shown in Figs. 2 90 and 3, its rim 28 is in such a position as to prevent the introduction of an implement or tool through the opening 19 to engage the valve 30 or with the same in the open position, as shown in Fig. 3, so that when 95 the suction action is stopped, the vacuum action within the bottle will draw the valve 30 upon the gasket 13 or 13' and consequently seal the opening 14 or 14' and thus 100 prevent the entrance of liquid within the bottle.

In order to provide a means for automatically sealing the opening or outlet 19, so that dust or other foreign matter cannot 105 enter the cap 15, when the bottle is upon a shelf or in the position to be readily de-cantered, the stem 33 is attached to the protecting member 25, as illustrated in Fig. 10, and extends through the opening 19, carrying the disk or cap 34, but when the bottle 110 is in the uprighted position as shown in Fig. 1, the parts will assume the position as shown in Fig. 10, closing the opening 19, the disk 34 when the bottle is tilted to the 115 position as shown in Figs. 2 and 3, moving a slight distance from the top of the cap 15 so that the said disk will act as an auxiliary means to prevent the introduction of a tool within the opening 19.

It will thus be seen that by making the valve member 30 and the protector 25 independent of each other, the valve protector being formed to have a straight line movement within the cap 15, that the protector member when the bottle is in a vertical position will insure of the proper centering of the valve 30 upon the gasket so that the opening 14 or 14' will be covered thereby. The movement of the parts to a horizontal 125 position, as shown in Fig. 2, permits the 130

member 25 to move slightly forward so that the valve 30 will slide downwardly to uncover the upper edge of the opening 14 sufficiently to permit of the introduction of air 5 and consequently the proper flowing of the liquid out of the opening 19 when the parts are in the position as shown in Fig. 3. By this means, the flow is a steady flow, and does not tend to spurt or squirt as is the 10 trouble with most of the structures heretofore marketed.

When the form shown in Fig. 10, is employed, a readily detached sealing cover or cap (not shown) composed of soft metal 15 may be used, the same being removed when it is desired to decant the liquor.

In order to prevent the valve 30 from adhering to the protector 25, the vent groove 35 is formed in the rim thereof.

20 What is claimed is:

1. A tubular discharge member having longitudinal guide ribs therein, a valve seat at the inner ends of the ribs, the ribs being offset outwardly adjacent the valve seat, a 25 valve within the offset portion of the ribs and seatable against the valve seat, and a baffle guided by the ribs beyond said offset portions thereof and having a flared flange seating within said offset portions of the ribs to limit the outward movement of the baffle and to engage over the periphery of the valve, whereby the movement of the baffle toward the valve seat will center and seat the valve.

35 2. A tubular discharge member, a valve

seat adjacent one end thereof, a valve within the member seatable against the valve seat, a baffle having a flared flange fitting within and guided by the discharge member and disposed to fit over, center and seat the 40 valve, and means disposed in coöperative relation to the flange for limiting the movement of the baffle toward the outlet of the discharge member.

3. A tubular discharge member, a valve 45 seat adjacent one end thereof provided with a port having a plurality of peripheral projections, a valve within the member seatable against the valve seat, said valve being capable of slight lateral movement whereby one 50 or more of the projections of the seat when the discharge member is tilted to a horizontal plane will be uncovered, a baffle having a flared flange fitting within and guided by the discharge member, and means intermediate of the ends of the discharge member for limiting the outward movement of the baffle, the flange of the baffle being disposed to engage over the periphery of the valve, whereby the movement of the baffle 55 toward the valve seat will center and seat the valve.

In testimony that I claim the foregoing as my own, I have hereto affixed my signature in the presence of two witnesses.

GUSTAVE GLOCKER.
